H. D. SCHMIDT,
GUMMING APPARATUS FOR RIBBON CUTTING MACHINES,
APPLICATION FILED AUG. 28, 1917.

1,266,058.

Patented May 14, 1918.

UNITED STATES PATENT OFFICE.

HENRY D. SCHMIDT, OF ASTORIA, NEW YORK.

GUMMING APPARATUS FOR RIBBON-CUTTING MACHINES.

1,266,058.

Specification of Letters Patent.

Patented May 14, 1918.

Application filed August 28, 1917. Serial No. 188,585.

To all whom it may concern:

Be it known that I, HENRY D. SCHMIDT, a subject of the Emperor of Austria, residing at Astoria, L. I., in the county of Queens 5 and State of New York, have invented certain new and useful Improvements in Gumming Apparatus for Ribbon-Cutting Machines, of which the following is a specification.

10 This invention relates in general to gumming apparatus and is directed particularly to an apparatus of this character adapted to be used in conjunction with ribbon cutting machines or the like. In the ordinary 15 use of these machines after the ribbon has been cut into strips a rough edge is left by the cutter which may easily cause the ribbon to fray or fringe. To prevent this a layer of some adhesive substance is usually 20 applied to the newly cut ribbon edge.

My main object in this invention, therefore, is to provide a gumming apparatus which may readily apply the layer of adhesive substance to the newly cut ribbon during 25 the cutting process.

Another object of my invention is to provide an apparatus of this character having means for varying the thickness of the layer of adhesive substance.

30 A further object of my invention is to provide an apparatus of the character described having means for the adjustment thereof relative to the cutting knives.

A still further object of this invention is 35 to provide a gumming apparatus which may be easily attached to the ordinary forms of ribbon cutting or like machines, readily manipulated, efficient in its operation and inexpensive to manufacture.

40 Further objects and advantages of this invention will appear from the detailed description and the features of novelty will be more particularly pointed out in the appended claims.

45 In the drawing forming a part of this specification, Figure 1 is an elevational view partly in section showing the essential parts of a ribbon cutting machine with an embodiment of my novel gumming apparatus attached thereto; Fig. 2 is an elevational view of an embodiment of the gumming apparatus itself; Fig. 3 is a plan view thereof, and Fig. 4 is an enlarged detailed

section taken along line 4—4 of Fig. 2, showing the means for adjusting the gumming apparatus relative to the circular cutting knives.

Referring in detail to the drawing, 10 represents a roll of ribbon 10¹ which is made to unwind over a roll 11 disposed in operative relation to a circular cutting knife 12. The cut ribbon unwinds from said roll 11 onto auxiliary rolls, such as 13 and 14. As is usual in the ordinary form of ribbon cutting machines, the roll of ribbon 10 is kept compact by means of the small rollers 15 and 16 held down against the material by the weight of the member 17.

My novel gumming apparatus will now be described. As will be clear from the drawing, the embodiment of my invention therein shown comprises a container or trough 18 which serves as a receptacle for any suitable gumming substance, preferably in liquid form. A bar 19 is milled out on one end to provide a recess 20 within which 75 rotates a wheel or roller 21 mounted on a shaft 22 passing through the bar. As will be clear from Fig. 1, the circular cutter 12 and this gumming roller 21 are in frictional contact and the rotary motion of the former is imparted to the latter. The bar 19 is mounted on the stand or frame 23 of the ribbon cutting machine and is so disposed relative to the gumming trough that the 80 gumming roller 21 dips thereto. It will now be clear that as the circular cutter 12 rotates, the cutting edge thereof has applied thereto the layer of adhesive substance through contact with the gummed roller, 85 and this layer is in turn applied by the cutter to the ribbon during the operation thereof as clearly shown in Fig. 1.

To provide for varying thicknesses of adhesive substances I preferably form the bar 19 with a projection 24 adapted to hold a curved blade or evener 25 which extends through the recess 20 in the bar over the roller 21 in spaced relation thereto. A set screw 26 operates through an opening in the 100 end 27 of the bar and is adapted to force the evener 25 which is somewhat resilient toward the gumming roller. The thickness of the layer of adhesive substance is thus regulated by said evener according to its 105 adjustment.

To keep the apparatus in position relative to the trough and in frictional contact with the cutter, I provide preferably a counterpoise 28 held on the opposite end 29 of the bar by means of the screw 30.

It is desirable in an apparatus of the nature described herein to provide means for the adjustment thereof relative to the circular cutting knives. I, therefore, preferably 10 form the bar 19 with a hole 31 adapted to receive a screw 32. The material of the bar about the opening 31 is cut away as at 33 to permit a sleeve 34 to be slipped thereover from one face of the bar, the collar 35 for 15 the sleeve being secured on the other face in some suitable manner. A nut 38 having at one end a removable head 39 is mounted on the screw 32 and carries the sleeve 34. By manipulation of the nut 38 the whole apparatus 20 may be adjusted relative to the circular cutting knives 12. Of course, other methods for accomplishing this adjustment will readily occur to one skilled in the art, and I do not limit myself to the specific construction hereinabove described and explained.

It will thus be clear that I have provided a novel gumming apparatus readily attached to ribbon cutting or like machines having 30 means for varying the thickness of the layer of gum to be applied to the cut ribbon, means for adjusting the position of the gumming apparatus relative to the cutting knives and yet withal simple in construction, effective in operation, easy to manipulate and comparatively inexpensive to make.

It will be understood, of course, that I do not limit myself to the specific structure shown in the drawing, since many changes 40 may be made in the construction without departing from the spirit of my invention.

Having thus described my invention, what I claim and desire to secure by Letters Patent is:

- 45 1. In a ribbon cutting apparatus or the like, the combination with a cutter, of means for applying a layer of adhesive material to the cutting edge simultaneously with the cutting operation.
- 50 2. In a ribbon cutting apparatus or the like, the combination with a cutter, of means for applying a layer of adhesive material to the cut edge of the material simultaneously

with the cutting operation whereby the said edge is gummed to prevent fraying thereof. 55

3. In a ribbon cutting apparatus or the like, in combination with a cutter, means co-operating with the latter for gumming the cut edge of the material.

4. A gumming apparatus comprising in 60 combination with a cutter, a container for gumming material, and a rotary means dipping thereto and adapted to co-operate with the cutter and apply the gumming material to the cutting edge thereof. 65

5. In a ribbon cutting apparatus or the like, in combination with a cutter, means co-operating with the latter for applying a layer of adhesive material to the cutting edge thereof and means for varying the 70 thickness of the layer of adhesive material.

6. In a ribbon cutting apparatus or the like, in combination with a cutter, means co-operating with the latter for applying a layer of adhesive material to the cutting 75 edge thereof and means for adjusting the gum applying means relative to the cutter.

7. In a ribbon cutting apparatus or the like, in combination with a cutter, means co-operating with the latter for applying a 80 layer of adhesive material to the cutting edge thereof, means for varying the thickness of said layer and means for adjusting the position of said gumming means relative to the cutter. 85

8. A ribbon cutting machine or the like comprising a roll carrying the ribbon to be cut, circular cutters and circular means in frictional contact with said cutters for applying a layer of adhesive substance to the 90 cutting edge of said cutters simultaneously with the cutting operation.

9. A gumming apparatus for material to be cut into strips comprising in combination with a circular cutter, circular gumming 95 means adapted to apply the gum to the edge of said cutter during the cutting operation and held continuously in frictional contact therewith.

In testimony whereof I affix my signature 100 in presence of two witnesses.

HENRY D. SCHMIDT.

Witnesses:

MAX D. ORDMANN,
A. M. WATTENBERG.

DISCLAIMER.

1,266,058.—*Henry D. Schmidt*, Astoria, N. Y. **GUMMING APPARATUS FOR RIBBON-CUTTING MACHINES.** Patent dated May 14, 1918. Disclaimer filed October 23, 1918, by the assignee, *The Bias Narrow Fabric Co.*

Enters this disclaimer—

“To said claims 1, 2, and 3, which are in the following words:

“1. In a ribbon cutting apparatus or the like, the combination with a cutter, of means for applying a layer of adhesive material to the cutting edge simultaneously with the cutting operation.

“2. In a ribbon cutting apparatus or the like, the combination with a cutter, of means for applying a layer of adhesive material to the cut edge of the material simultaneously with the cutting operation, whereby the said edge is gummed to prevent fraying thereof.

“3. In a ribbon cutting apparatus or the like, in combination with a cutter, means coöperating with the latter for gumming the cut edge of the material.”
